HIS ATTORNEY

UNITED STATES PATENT OFFICE.

CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

1,161,915.

Specification of Letters Patent. Patented Nov. 30, 1915.

Application filed August 25, 1915. Serial No. 47,250.

To all whom it may concern:

Be it known that I, CLIO B. YAW, citizen of the United States, and resident of Arlington, in the county of Hudson, and State of New Jersey, have invented certain new and useful Improvements in Type-Writing Machines, of which the following is a specification.

My invention relates to typewriting machines and more particularly to work sheet feeding means.

The main object of the present invention, generally stated, is to provide simple, inexpensive and yet highly efficient auxiliary feeding means by which a stencil card or like may be fed effectively in a cylindrical platen machine in substantially a flat condition, so that the cards or work sheets need not be bent with a consequent liability of mutilating or breaking them as they are being fed through the machine.

A further and important object of my invention is to provide means of the character specified which are in the nature of an attachment that may be readily applied to or detached from typewriting machines now on the market, without modifying the structural features of said machines, as they now exist, and without impairing the usefulness of said machines for ordinary work in which the work sheets are fed around the platen.

To the above and other ends which will hereinafter appear, my invention consists in the features of construction, arrangements of parts and combinations of devices set forth in the following description and particularly pointed out in the appended claims.

In the accompanying drawings wherein like reference characters indicate corresponding parts in the different views, Figure 1 is a front elevation, with parts broken away and parts omitted, of a carriage of a Monarch typewriting machine equipped with the auxiliary feed devices of my invention. Fig. 2 is a vertical fore and aft sectional view of the same, the carriage being shown mounted in place in the machine. Fig. 3 is a detail vertical fore and aft sectional view with parts broken away, the view showing one of the margin feed devices and some of the associated parts, and the section being taken on the line $x-x$ of Fig. 1 and looking in the direction of the arrows at said line.

Fig. 4 is a detail plan view of one of the margin feed devices shown detached. Fig. 5 is a detail perspective view of one form of card feeding mechanism embodying my invention, together with some of the associated parts. Fig. 6 is an enlarged detail sectional view taken on the line $y-y$ of Fig. 3 and looking in the direction of the arrow at said line. Fig. 7 is a detail perspective view of a modified form of card feeding attachment constructed in accordance with my invention.

I have shown my invention embodied in the present instance in a Monarch machine in which the invention may be readily incorporated without modifying the structural features of said machine as they now exist, and without rendering the machine any the less effective to perform its ordinary work. It should be understood, however, that the invention may be embodied in other styles of typewriting machines and that various changes may be made to readily effect such embodiment.

In the accompanying drawings I have shown only so much of the Monarch machine as may be necessary to arrive at an understanding of my present invention, parts of the usual equipment of said machine being omitted where it is unnecessary to such understanding.

The top plate 1 of the machine supports the usual uprights 2 to which fixed oppositely grooved guide rails 3 are secured by screws 4. These grooved guide rails receive anti-friction balls or rollers 5 which are also received in oppositely grooved rails 6 of a guide bar 7, which constitutes part of the carriage of the machine. End plates 8 project forward from this guide bar and support a platen shaft 9 on which the usual cylindrical platen 10 is mounted. The usual paper feed mechanism of the machine is employed, the main paper feed rollers 11 and 12, respectively, a paper apron 13, paper table 14 and scale plate 15 being diagrammatically shown in Fig. 2 of the drawings. The left-hand platen head is provided with a line spacing ratchet wheel 16 with which a line spacing pawl 17 cooperates. This pawl is pivoted at 18 to a supporting arm 19 operated by a rock shaft controlled by a finger piece 20.

The usual margin feed devices and erasing shelf or plate employed in the Monarch machine are included in the present construction and by means of which the auxiliary feed devices of my present invention may be 5 detachably mounted in place as will herein-after more clearly appear. The usual cross rod 21 is arranged above the platen and is secured at its ends to the end plates 8 of the 10 platen frame and supports the margin feed devices for adjustment longitudinally of said cross rod and the platen with which they co-act. This rod also constitutes a support for the erasing plate designated as a whole 15 by the reference numeral 22. This plate is formed with ears 23 which are received in reduced bearing portions of the cross rod and thus support the plate at one end by the rod, the forward edge of the erasing 20 plate bearing against the face of the platen. The rod 21 is formed with a spline groove 24 (see Fig. 6) which extends throughout the length of the rod.

Each of the usual margin feed devices is 25 formed with a bearing sleeve 25 which surrounds the supporting rod 21. Each sleeve co-acts with a spring spline member 26 which is received in a spline groove 24 of the rod 21, to hold the associated sleeve and 30 the parts carried thereby against turning movement on the rod 21 but enables the sleeves with the parts carried thereby to be adjusted along the cross or supporting rod. A rigid forwardly extending arm 27 is 35 formed on each sleeve 25 and has pivoted thereto at its forward end an arm 28 which carries an inwardly projecting spindle 29 surrounded by a spacing sleeve and supporting a margin feed roller 30. A spring- 40 pressed plunger 31 co-acts with faces 32 or 33 on the end of the associated arm 27 to maintain the margin feed roller in either its operative or inoperative position. Each arm 27 has a paper finger 34 pivoted there- 45 to at 35, each finger being formed with an offset outwardly projecting arm 36 provided with a yoke 37 which is substantially U-shaped in cross section. The side members of the yoke are pivoted at 35 to the associated arm 27, said members being connected by a cross plate 38. An expansion 50 spring 39 is received in an opening in the arm 27 which carries it and bears at its lower end against the cross plate 38 of the 55 yoke of the associated paper finger 34. The pressure of each spring 39 is thus exerted to force the associated paper finger against the platen.

A further detailed description of the 60 paper fingers, margin feed rollers and erasing shelf or plate is deemed unnecessary since they are of the usual construction embodied in the Monarch machine, said paper fingers and margin feed roll construction being of the character disclosed in the patent

to Seib No. 921,745, dated May 18, 1909, and the erasing shelf or plate being substantially of the character represented in the patent to Nielsen No. 790,652, dated May 23, 1905.

While I have described with considerable detail the margin feed mechanism, it should be understood that this description is primarily for the purpose of showing the manner in which the mechanism in question co-operates with the card feed mechanism in a front-strike typewriting machine to detachably secure said mechanism in place.

From certain aspects of my invention it is immaterial what character of margin feed devices are employed so long as they co-act 80 with the auxiliary feed devices to hold the latter in place and afford a detachment thereof.

One form of the attachment by which the cards or work sheets may be effectively fed 85 in the machine is disclosed in Fig. 5, from which it will be seen that the attachment or device in question comprises a supporting bar, member or plate 40. This supporting member is formed with bearing portions 41 90 apertured to receive a bearing spindle 42 which forms a support for a two-part hollow rock shaft 43—44. The inner ends of the hollow shaft are united by a joint comprising feathers or lugs 45 on the inner end 95 of one member of the shaft which are received in corresponding openings or cutouts 46 in the other member to form an interlocking engagement between the two to cause them to turn together. There is a 100 slight lost motion between the feathers 45 and the walls of the openings 46 in which they are received, as indicated at 47, in order to afford a slight lost motion between the two members of the shaft and thus provide for a limited independent rotative movement between them, for purposes which will herein-after more clearly appear. Each member of the rock shaft 43—44 carries a 105 depending arm 48 fixed thereto in any suitable manner. Each arm 48 is apertured to receive a spindle 49 which is in the nature of a headed shouldered screw secured in place by a lock nut 50. Each spindle projects inwardly from its supporting arm 48 110 and carries an auxiliary or card feed roller 51, located at or near the printing line and adapted to co-operate with a side edge portion of a card or like work sheet, indicated as a whole by the letter A. Each arm 48 is 115 extended rearwardly above the supporting bar 40 and beyond the member of the rock shaft to which it is attached, as indicated at 52. A leaf spring 53 bears at its free end upwardly against each of the rearwardly 120 extending portions 52 of the arms 48 causing the auxiliary feed rollers 51 to bear against the platen, or the card interposed between the feed rollers and the platen. The outer ends of the springs 53 are secured at 54 to 125

the supporting member 40. It will be understood that each of the springs 53 acts individually on its associated feed roller 51, this individual pressure of each feed roller by its spring against the card being afforded by the lost motion between the two members of the rock shaft 43-44. The purpose of this is to enable each feed roller 51 to exert its spring pressure against the card independently of the other in order to effectively co-act with and feed the card at one side even though the roller at the other side of the card be slightly displaced forwardly from the platen by reason of any inequality or unevenness in the card. In this manner an effective engagement is at all times maintained between the feed rollers 51 and the card while the latter is engaged by the feed rollers.

One of the arms 48 is provided with an upwardly extending member 55 which terminates in a finger piece 56. By moving the latter rearwardly against the pressure of the associated spring 53, the feed roller 51 carried by said arm is moved forwardly away from the platen or work sheet and the member 43 of the two-part rock shaft is turned. When the limit of independent movement between the two members of the shaft is reached the member 44 will be turned, thus releasing the other feed roller 51 from operative engagement with the card.

The supporting member 40 which carries the auxiliary feed rollers is detachably secured in place in operative position in the following manner: From an inspection of Figs. 2 and 5 it will be seen that the supporting member is formed with depressions or recesses 57 which constitute bearing seats which, in the present instance, co-operate with the sleeves 25 of the margin feed devices to support the member 40 and the parts carried thereby on the cross rod 21. The ends or terminal portions 58 of the supporting member 40 are adapted to be received under the connecting members or plate 38 of the paper fingers, as illustrated in Fig. 3, and to be pressed by the spring 39 against the erasing plate 22 and on the cross rod 21 or the sleeves 25 carried thereby, and thus clamp and secure the supporting member 40 in operative position.

In attaching the member 40 to the machine, one end 58 thereof is first introduced into position between the spring pressed plate 38 of the associated paper finger and the erasing shelf. The seat 57 at this end of the member 40 will bear at this time against the sleeve 25 of the associated paper finger. The other margin feed device will then be adjusted inwardly along the supporting rod until its spring pressed plate 38 extends over the opposite end 58 of the supporting member 40 and the seat 57 at this end of the member is seated on the as-

sociated sleeve 25, and the member 40 will then be held firmly in position. When thus positioned the support 40, together with the parts carried thereby, are effectively supported in operative position ready to receive a card or like work sheet and to co-operate with the platen as the latter is line spaced to effectively feed the card while the latter is maintained in a substantially flat condition in front of the platen, as indicated in Figs. 1 and 5.

In order to remove the attachment it is merely necessary to effect an outward displacement of the sleeves 25, and the parts which are carried thereby, away from each other when the member 40 will be released and may be removed from the machine.

The construction disclosed in Fig. 7 is similar to that disclosed in the preceding figures except that the parts have been simplified. Thus, in the modified form of construction the supporting member 59 is struck up from a single piece of sheet metal formed with supporting ears or hooks 60 which constitute seats to engage the sleeves 25 on the margin feed devices. Ears 61 are likewise formed on the supporting member to receive the spindle 62 which supports the two-part rock shaft 63, 64. The abutting ends of these members of the shaft are cut-out, as at 65, to provide an interlocking engagement between the two members which causes one to turn with the other, a slight lost motion being provided, as indicated at 66, to afford a limited independent turning movement between the two members of the shaft. A single spring 67 is secured by screws 68 to the supporting member so that opposite ends of the springs bear upwardly on the rearwardly projecting ends of the arms 69 and 70 which carry the auxiliary feed rollers 71. The opposite ends of this spring are in effect individual springs which operate individually on the associated roller carrying arms in the same manner and for the same purpose as the individual springs 53 in the previously described construction. The arm 70 is formed with a finger piece 72 by which the auxiliary feed rollers may be released. The attachment disclosed in Fig. 7 is mounted and secured in position in the same manner as the previously described attachment and co-operates with the platen in the same manner to effect a feed of the cards.

When I refer herein to a "card" I use that term in a broad sense to designate more particularly a work sheet such as a stencil card or sheet of the character shown, cards such as are used for card index systems, envelopes or any other work sheet which by reason of its thickness or construction renders it desirable that it shall be maintained substantially in a flat condition while it is being fed through the machine. It should be understood, however, that the term is not neces-

sarily restricted to a "card" of the character specified and that from certain aspects of the invention the mechanism may be employed to feed the work sheets in any available manner and may be employed in connection with work sheets of any suitable character.

Various changes may be made without departing from the spirit and scope of my invention.

What I claim as new and desire to secure by Letters Patent, is:—

1. In a typewriting machine, the combination of a platen, margin feed devices, auxiliary feed devices coöperative with the platen, and a supporting member which is detachably held in place by the margin feed devices and carries said auxiliary feed devices.

2. In a typewriting machine, the combination of a platen, auxiliary feed devices coöperative with the platen, a two-part rock shaft which carries said devices, means for enabling the members of said shaft to receive a limited rotative movement independently of each other, and means for applying spring pressure to one of said devices independently of the other.

3. In a typewriting machine, the combination of a platen, card feeding devices coöperative with the platen, a two-part rock shaft which carries said devices, means for enabling the members of said shaft to receive a limited rotative movement independently of each other, means for applying spring pressure to one of said devices independently of the other, and a finger piece operative to release said card feeding devices.

4. In a typewriting machine, the combination of a platen, a detachable supporting member, auxiliary feed rollers carried thereby and pivoted thereon for a limited independent movement toward and away from the platen, separately acting spring means for said auxiliary feed rollers, and margin feed devices which coöperate with said supporting member to hold it in place with the auxiliary feed rollers in coöperative relation with the platen.

5. In a typewriting machine, the combination of a platen, margin feed devices, an erasing plate, a detachable support held in place between said margin feed devices and said erasing plate and by the engagement of said margin feed devices therewith, and auxiliary feed devices carried by said support.

6. In a typewriting machine, the combination of a platen, margin feed devices, an erasing plate, a detachable supporting bar held in place between said margin feed devices and erasing plate, the margin feed devices being adjustable longitudinally of the platen over the ends of the supporting bar to engage the latter and hold it in place, and

pivotaly supported spring-pressed auxiliary feed rollers carried by said detachable supporting bar.

7. In a typewriting machine, the combination of a platen, a cross rod supported above the platen, margin feed devices carried by and adjustable along said cross rod, a supporting member detachable from said cross rod and recessed to form a seat, said supporting member being held in place by the margin feed devices which are adapted to overlie and bear against the supporting member, and auxiliary feed devices carried by said supporting member.

8. In a typewriting machine, the combination of a platen, a cross rod supported above the platen, margin feed devices carried by and adjustable along said cross rod, a supporting member detachable from said cross rod and recessed to form a seat, said supporting member being held in place by the margin feed devices which are adapted to overlie and bear against the supporting member, arms pivoted on the supporting member, auxiliary feed rollers carried by said arms, and spring means for forcing said auxiliary feed rollers against the platen.

9. In a typewriting machine, the combination of a platen, a cross rod supported above the platen, margin feed devices carried by and adjustable along said cross rod, a supporting member detachable from said cross rod and recessed to form a seat, said supporting member being held in place by the margin feed devices which are adapted to overlie and bear against the supporting member, arms pivoted on the supporting member, auxiliary feed rollers carried by said arms, means for affording a limited relative pivotal movement between said arms, means for applying individual spring pressure to said arms, and a finger piece operative to move both arms and release the auxiliary feed rollers from the platen.

10. In a typewriting machine, the combination of a platen, a two-part rock shaft, means for affording a limited rotative movement of one member of said shaft relatively to the other member, an arm carried by each of said members, and a feed roller carried by each of said arms.

11. In a typewriting machine, the combination of a platen, a two-part rock shaft, means for affording a limited rotative movement of one member of said shaft relatively to the other member, an arm carried by each of said members, a feed roller carried by each of said arms, means for applying individual spring pressure to each of said arms, and a finger piece connected to one member of said shaft and operative to release both feed rollers.

12. In a typewriting machine, the combination of a platen, a detachable support, a two-part rock shaft, means for affording a

- limited rotative movement of one member of said shaft relatively to the other member, an arm fixed to each member of said shaft, an auxiliary feed device carried by each of said 5 arms and coöperative with the platen, and means for applying spring pressure to each of said arms independently of the other, all of said parts except the platen being carried by and detachable with said support.
- 10 13. In a typewriting machine, the combination of a platen, a detachable support, a two-part rock shaft, means for affording a limited rotative movement of one member of said shaft relatively to the other member, an arm fixed to each member of said shaft, a card feeding device carried by each of said arms and coöperative with the platen, means for applying spring pressure to each of said arms independently of the other, and
- 15 20 a finger piece operative to move both of said arms against the spring pressure thereon and release both card feeding devices from the platen, all of said parts except the platen being carried by and detachable with said 25 support.
14. In a typewriting machine, the combination of a platen, spring-pressed paper fingers, a detachable supporting member which is clamped in place by said paper fingers, 30 and auxiliary feeding devices carried by said detachable supporting member.
15. In a typewriting machine, the combination of a platen, an erasing plate, spring-pressed paper fingers, a detachable supporting member adapted to be received between the erasing plate and paper fingers and to be clamped in place by the latter, and auxiliary feed devices carried by said supporting 35 member.
- 40 45 16. In a typewriting machine, the combination of a platen, a platen frame, a cross rod carried by the platen frame, spring-pressed paper fingers carried by said cross rod, a supporting member detachable from said rod and recessed to form a seat and adapted to be clamped in place by said paper fingers, and auxiliary feed devices carried by said supporting member.
- 50 55 17. In a typewriting machine, the combination of a platen, a platen frame, a cross rod carried by the platen frame, spring-pressed paper fingers carried by said cross rod and adjustable along the same, a supporting member detachable from said cross rod and recessed to form a seat and over the ends of which the spring-pressed paper fingers are adapted to be adjusted to clamp the supporting member in place, auxiliary feed rollers carried by said supporting member 60 and coöperative with each of said arms, and auxiliary feed devices carried by each of said arms.
- 65 18. In a typewriting machine, the combination of a platen, a platen frame, a cross rod carried by the platen frame, a supporting member detachable from said cross rod and provided with a bearing seat, spring-pressed margin feed devices adapted to overlie the detachable supporting member and clamp the same in place, and auxiliary feed devices carried by said supporting member 70 and coöperative with the platen between said margin feed devices.
19. In a typewriting machine, the combination of a platen, a platen frame, a cross rod carried by the platen frame, an erasing plate carried by said cross rod, a supporting member detachable from said cross rod and provided with a bearing seat, spring-pressed margin feed devices adapted to overlie the ends of the detachable supporting member 75 and clamp the same in place against the erasing plate and on the cross rod, and auxiliary feeding devices carried by said detachable supporting member.
20. In a typewriting machine, the combination of a platen, a platen frame, a cross rod carried by the platen frame, an erasing plate carried by said cross rod, a supporting member detachable from said cross rod and provided with a bearing seat, spring-pressed margin feed devices adapted to overlie the ends of the detachable supporting member 80 and clamp the same in place against the erasing plate and on the cross rod, spring-pressed pivoted arms carried by said 85 supporting member, and auxiliary feed rollers carried by said arms, whereby the supporting member with the parts carried thereby may be readily attached to or detached 90 from the machine.
- 100 21. In a typewriting machine, the combination of a platen, a platen frame, a cross rod carried by the platen frame, an erasing plate carried by said cross rod, a supporting member detachable from said cross rod and provided with a bearing seat, spring-pressed margin feed devices adapted to overlie the ends of the detachable supporting member 105 and clamp the same in place against the erasing plate and on the cross rod, a two-part rock shaft carried by said supporting member, means for affording a limited rotative movement of one member of said shaft independently of the other, an arm fixed to each member of the two-part shaft, a spring 110 coöperative with each of said arms, and auxiliary feed devices carried by each of said arms.
- 115 22. In a typewriting machine, the combination of a platen, a platen frame, a cross rod carried by the platen frame, an erasing plate carried by said cross rod, a supporting member detachable from said cross rod and provided with a bearing seat, spring-pressed margin feed devices adapted to 120 overlie the ends of the detachable supporting member and clamp the same in place against the erasing plate and on the cross rod, a two part rock shaft carried by said 125 supporting member, means for affording a 130

limited rotative movement of one member of said shaft independently of the other, an arm fixed to each member of the two-part shaft, a spring coöperative with each of 5 said arms, an auxiliary feed roller carried by each of said arms and coöperative with the platen, and a finger piece carried by one of said arms and operative to turn the two-part shaft and release both auxiliary feed 10 rollers.

23. In a typewriting machine, the combination of a carriage, a platen carried thereby, a supporting plate or bar carried by the carriage, a spindle carried by said plate or 15 bar, a two-part hollow shaft adapted to turn on said spindle, a joint between the members of said hollow shaft which affords a limited turning movement of one member of the shaft relatively to the other member, independent 20 auxiliary feed devices carried by the members of said shaft, and spring means for forcing said auxiliary feed devices against the platen.

24. In a typewriting machine, the combination of a carriage, a platen carried thereby, a supporting plate or bar carried by the carriage, a spindle carried by said plate or bar, a two-part hollow shaft adapted to turn on said spindle, a joint between the members 30 of said hollow shaft which affords a limited turning movement of one member of the shaft relatively to the other member, independent auxiliary feed devices carried by the members of said shaft, spring means for 35 forcing said auxiliary feed devices against the platen, a finger piece connected with one member of the two-part shaft for turning it and its companion member as well and thus releasing the auxiliary feed devices, and 40 means for detaching said supporting bar or plate together with the parts carried thereby from the carriage.

25. In a front-strike typewriting machine, the combination of a cylindrical platen; margin feed devices; and auxiliary feeding means for feeding a card or the like 45 while it is maintained substantially in a flat condition, said auxiliary feeding means comprising a detachable supporting member 50 which is detachably held in place by said margin feed devices, and auxiliary feed devices which co-act with the side edge portions of the card near the printing line and which are carried by said detachable supporting member.

26. In a front-strike typewriting machine, the combination of a cylindrical platen; spring-pressed margin feed devices; and auxiliary feeding means for feeding a card 60 or the like while it is maintained substantially in a flat condition in front of the platen, said auxiliary feeding means comprising a detachable supporting member which is clamped in place by said spring-pressed margin feed devices, spring-pressed 65

feed rollers which co-act with the side edge portions of the card near the printing line and which are carried by said detachable supporting member, and means operable at will to release said feed rollers.

27. In a front-strike typewriting machine, the combination of a carriage; a cylindrical platen carried thereby; a cross rod carried by the carriage and arranged above the platen; forwardly extending rigid arms carried by and adjustable along said cross rod but fixed against turning movement thereon; a spring-pressed margin feed device carried by each of said rigid arms; and auxiliary feeding means for feeding a card or the like while it is maintained substantially in a flat condition in front of the platen, said auxiliary feeding means comprising a detachable supporting member adapted to be received beneath said rigid arms and clamped in place by said spring-pressed margin feed devices, and auxiliary feed devices carried by said detachable supporting member.

28. In a front-strike typewriting machine, the combination of a carriage; a cylindrical platen carried thereby; a cross rod carried by the carriage and arranged above the platen; forwardly extending rigid arms carried by and adjustable along said cross rod but fixed against turning movement thereon; a spring-pressed margin feed device carried by each of said rigid arms; and auxiliary feeding means for feeding a card or the like while it is maintained substantially in a flat condition in front of the platen, said auxiliary feeding means comprising a detachable supporting member adapted to be received beneath said rigid arms and clamped in place by said spring-pressed margin feed devices, and auxiliary feed devices carried by said detachable supporting member and coöperative with the side edge portions of a card or the like near the printing line, and means for releasing said auxiliary feed rollers.

29. In a front-strike typewriting machine, the combination of a carriage; a cylindrical platen carried thereby; a cross rod carried by the carriage and arranged above the platen; an erasing plate carried by said rod; forwardly extending rigid arms carried by and adjustable along said cross rod but fixed against turning movement thereon; a spring-pressed paper finger carried by each 110 of said rigid arms; and auxiliary card feeding means comprising a detachable supporting member adapted to be received between the paper fingers and erasing plate and clamped in place by said spring-pressed paper fingers, and auxiliary feed rollers carried by said detachable supporting member and coöperative with the side edge portions of a card or the like near the printing line.

30. In a front-strike typewriting machine,

the combination of a carriage; a cylindrical platen carried thereby; a cross rod carried by the carriage and arranged above the platen; an erasing plate carried by said rod; 5 forwardly extending rigid arms carried by and adjustable along said cross rod but fixed against turning movement thereon; a spring-pressed paper finger carried by each of said rigid arms; an auxiliary card feeding means 10 comprising a detachable supporting member adapted to be received between the paper fingers and erasing plate and clamped in place by said spring-pressed paper fingers, downwardly extending spring-pressed arms 15 pivoted on said supporting member intermediate the paper fingers, and feed rollers carried by said arms.

31. In a front-strike typewriting machine, the combination of a carriage; a cylindrical platen carried thereby; a cross rod carried by the carriage and arranged above the platen; an erasing plate carried by said rod; 20 forwardly extending rigid arms carried by and adjustable along said cross rod but fixed against turning movement thereon; a spring-pressed paper finger carried by each of said rigid arms; and auxiliary card feeding means comprising a detachable supporting member adapted to be received between the 25 paper fingers and erasing plate and clamped in place by said spring-pressed paper fingers, said supporting member also being formed with a bearing seat by which it may be detachably supported by said cross rod, 30 spring-pressed auxiliary feed rollers carried by said detachable supporting member and coöperative with the side edge portions of a card or the like near the printing line, and means for releasing said auxiliary feed 35 rollers.

32. In a front-strike typewriting machine, the combination of a carriage; a cylindrical platen carried thereby; a cross rod carried by the carriage and arranged above the 40 platen; an erasing plate carried by said rod; forwardly extending rigid arms carried by and adjustable along said cross rod but fixed against turning movement thereon; a spring-pressed paper finger carried by each of said 45 rigid arms; and auxiliary card feeding means comprising a detachable supporting

member adapted to be received between the paper fingers and erasing plate and clamped in place by said spring-pressed paper fingers, said supporting member also being 55 formed with a bearing seat by which it may be detachably supported by said cross rod, a spindle carried by said supporting member, a two-part hollow shaft mounted to turn on said spindle, means for affording a limited 60 turning movement of each member of said two-part shaft relatively to the other member, a spring coöperative with each of said arms, a feed roller carried by each arm, and a finger piece on one of said arms and which 65 is operative to turn the two-part shaft to release both of said feed rollers.

33. In a front-strike typewriting machine, the combination of a cylindrical platen, margin feed devices, a supporting member 70 having an interlocking engagement with and detachable from said margin feed devices, and a pair of spring-pressed auxiliary feed rollers carried by said supporting member and coöperative with the platen near the 75 printing line to feed a card or the like substantially in a flat condition in front of the platen.

34. In a front-strike typewriting machine, the combination of a platen frame; a cylindrical platen carried thereby; a cross rod carried by the platen frame; and auxiliary 80 detachable feeding means for feeding a card or the like substantially in a flat condition in front of the platen, said auxiliary feeding 85 means comprising a supporting member detachable from said rod and provided with a bearing seat, means for detachably holding said supporting member in place where it is supported by the rod, and spring-pressed 90 auxiliary feed rollers carried by said supporting member and coöperative with the platen near the printing line.

Signed at the borough of Manhattan, city of New York, in the county of New York, 95 and State of New York, this 24th day of August, A. D. 1915.

CLIO B. YAW.
